ILLUMINATED ASH TRAY

William J. de Beaubien, Birmingham, Mich., assignor to
General Motors Corporation, Detroit, Mich., a corpora-
tion of Delaware

Application December 6, 1951, Serial No. 260,213

11 Claims. (Cl. 240—2)

This invention relates to an ash tray, and more particularly to an illuminated ash tray for an automobile.

One feature of the invention is that it provides an improved illuminated ash tray; another feature of the invention is that it provides means for providing a beam from a lamp when the ash receptacle is in one position and for blocking said beam when the receptacle is in another position; a further feature of the invention is that it provides means for illuminating the interior of the ash receptacle when said receptacle is fully open, and means for providing a beam of light rays outside of said receptacle when the receptacle is partially open; still another feature of the invention is that it provides a switch for controlling the operation of the lamp which is associated with the ash tray and a baffle on the movable ash receptacle for operating the switch upon movement of the receptacle and for controlling said beam; yet a further feature of the invention is that it provides an ash tray comprising a supporting frame, an ash receptacle slidably mounted on said frame for movement between open and closed positions, a lamp on said frame rearwardly of said receptacle, switch means adjacent said lamp, and a baffle mounted on said receptacle and extending rearwardly adjacent said lamp for providing a beam from the lamp when the receptacle is partially open, and for blocking the beam when the receptacle is fully open; yet another feature of the invention is that the receptacle is provided with an opening for admitting light into the interior thereof and means are provided for directing rays from the lamp toward said opening; and still a further feature of the invention is that the lamp is provided with a housing having openings for directing rays from the lamp, and the baffle is provided with a window adapted to be aligned with one of the openings in the lamp housing.

Other features and advantages of the invention will be apparent from the following description, and from the drawings in which:

Fig. 1 is a vertical transverse section through an automobile instrument panel having the improved ash tray mounted thereon, the ash tray being shown in closed position in solid lines, in partially open position in dotted lines, and in fully open position in broken lines. Figs. 2, 3 and 4 are enlarged views showing the ash tray in closed position, Fig. 2 being a partially broken away horizontal longitudinal section along the line 2—2 of Fig. 1; Fig. 3 being a transverse section along the line 3—3 of Fig. 1; and Fig. 4 being a partially broken away vertical longitudinal section. Figs. 5, 6 and 7 are enlarged views showing the ash tray in partially open position, Fig. 5 being a fragmentary section similar to a portion of Fig. 4; Fig. 6 being a longitudinal section along the line 6—6 of Fig. 5; and Fig. 7 being a transverse section along the line of 7—7 of Fig. 5. Figs. 8 and 9 show the ash tray in fully open position, Fig. 8 being a section similar to Fig. 6; and Fig. 9 being a section along the line 9—9 of Fig. 8.

The instrument panel of an automobile generally is provided with an ash tray for the convenience of the occupants of the automobile front seat. Unless the ash tray is illuminated at night it is often difficult to be sure that the ashes, etc., are deposited in the tray and are not dropped on the floor of the automobile. This invention provides an improved ash tray having means to illuminate the interior of the ash tray when the ash tray is fully open, and having means for directing a beam of light downwardly when the ash tray is partially open and for blocking said beam when the ash tray is fully open. The downwardly directed beam serves to illuminate the floor

2

of the automobile so that any article which may have been dropped can be easily located, and the beam may also serve as a map light or reading light. In order to provide the downwardly directed beam the ash receptacle is moved into an intermediate or partially open position. When the ash receptacle is moved to fully open position the beam is blocked, and the only light seen is a dim illumination in the interior of the ash receptacle to define its periphery so that articles may easily be deposited in the ash tray. When the ash receptacle is closed the lamp which provides the source of illumination is extinguished.

Referring more particularly to the drawings, the instrument panel 10 of an automobile has an opening 11 therein, behind which is mounted a supporting frame designated generally as 12, said frame providing a slideable mounting for an open-topped ash receptacle designated generally as 40. The frame 12 preferably is formed of two sheet metal stampings, the first being a top member having a plane portion 13 and a forward portion 14 which is bent upwardly to provide supporting means adapted to receive a machine screw 15 which secures the frame to a rearwardly bent bracket portion 10a of the instrument panel 10 of the automobile.

A metal strap 16 extends over the top portion 13 of the supporting frame and is secured by means of screws 17 to side plates 18 and 19 forming part of the second sheet metal stamping of the supporting frame. The lower portions of the metal strap 16 are bent inwardly to provide brackets 16a whereby the strap 16 may be mounted 20 on a reinforcing bracket positioned on a rearwardly bent lower portion 10b of the instrument panel 10. The side plates 18 and 19 preferably are formed from a single sheet metal stamping which is bent to provide a connecting portion 20 joining the side plates at the rear, said metal stamping being again bent to provide a horizontal portion 21 and a vertical portion 22 which provides a rear wall for the supporting frame 12. The words "forward" and "rear" are used in the sense of defining the ash tray parts per se—that is, the ash receptacle 40 is moved forwardly to open position and rearwardly to closed position. The side plates 18 and 19 are bent inwardly at 18a and 19a respectively to overlie the top 13, and the bottom edges of the side plates are bent inwardly at a right angle to provide flanges 18b and 19b. The outer edges of the front portion 14 of the top member are bent down and inwardly to provide channel tracks 14a and 14b upon which the ash receptacle 40 is slidable.

A lamp 24 is carried in a socket 25 mounted on the horizontal plate portion 21, the lamp bulb extending below the portion 21 into a lamp housing formed by said portion 21, the rear wall 20, the side plate 19, a front plate 26 having a window 26a therein, and an intermediate plate 27 extending forwardly from the wall 20 intermediate the side plates 18 and 19. The lamp housing is opened at the bottom, and preferably the surfaces of the lamp housing members are painted black to prevent undue reflection of rays from the lamp 24.

A single pole single throw switch 28 is mounted on the plate 21 at the side of lamp 24, said switch having an actuating member 29 projecting downwardly through the plate 21. The switch is spring biased to closed position, in which position the actuating member 29 projects downwardly to its fullest extent as shown best in Fig. 5. A lead 30 extends to one terminal of the switch, this lead being held in position by means of a clip 31 secured to the wall 18 of the supporting frame, and the other end of the lead being connected to a source of voltage, such connection preferably being through one of the lighting circuits of the automobile, as, for example, the tail light circuit. The other switch terminal is connected by means of a lead 32 to one terminal of the lamp, and, as is conventional in automobile lighting systems, the other lamp terminal is grounded.

The open-topped ash receptacle 40 is generally of conventional construction, having a bottom 41, a rear wall 42, opposite side walls 43 and 44, and a front wall 45 to which is secured an ornamental front plate 46. A handle 47 is mounted on the front of the receptacle by means of screws 48, and a snuffer 49 is formed by bending over a projecting portion of the front wall 45.

As illustrated in Figs. 4, 5, 7 and 9, the top edge of

the rear wall 42 of the ash receptacle is spaced from the lower surface of the member 13 to provide a slot 60 for the admission of light rays into the interior of the ash receptacle. Preferably the slot is of the order of $\frac{1}{16}$ inch wide. The upper portions of the receptacle sides are bent outwardly, then upwardly and inwardly to form rails 50 and 51, these rails being flattened throughout their forward extent and the respective flattened portions terminating in shoulders adapted to engage detents 52 in the channel tracks to provide stop means for the ash receptacle to limit sliding movement of the receptacle in the channel tracks.

A baffle 54 is secured to the ash receptacle bottom by means of screws 55, this baffle projecting rearwardly adjacent and beyond the lamp housing and the switch. At one side near the longitudinal center of the baffle a window 56 is provided. At the other side and somewhat forwardly of the window 56 the baffle is provided with a raised portion designated generally as 57 and having a rearwardly extending sloping or cam surface 58 and a flat raised center surface portion 59. The upper surface of the baffle 54 and the outer surface of the receptacle rear wall 42 preferably are painted black to minimize reflection.

In assembling the parts the ash receptacle 40 is slidably mounted on the supporting frame 12, the under surface of the baffle 54 riding upon the tracks 18b and 19b, and the rails of the receptacle sliding in the tracks 50 and 51. The rails may be squeezed together as the parts are assembled to facilitate the assembly. With the ash tray fully closed as shown in solid lines in Fig. 1 and as shown in Figs. 2, 3 and 4, the switch actuating member 29 rides up on the raised surface 59 on the baffle so that the switch is open, and the lamp 24 is extinguished even if the lighting circuits of the automobile are energized. When the ash receptacle is moved to a partially open position as shown in dotted lines in Fig. 1 and as shown in Figs. 5, 6 and 7, the switch actuating member 29 rides down the sloping cam surface 58, and the switch is closed. With the parts in this position, if the tail light circuit of the automobile is energized, the lamp 24 will be illuminated, and a beam of light rays from the lamp will be directed downwardly, passing through the window 56 which is now aligned with the open bottom of the lamp housing as shown best in Figs. 6 and 7. This beam of light will illuminate the floor of the automobile, and the beam may be also used as a map light or reading light.

When the ash tray is moved to its fully open position as shown in broken lines in Fig. 1, and as shown in Figs. 8 and 9, the window 56 moves forwardly of the lamp housing so that the beam of light is blocked by the baffle 54. However, light rays extending through the forward window 26a will enter the slot 60 between the top 13 of the supporting frame and the rear wall 42 of the ash receptacle to provide a dim illumination for the interior of the ash receptacle. When the ash receptacle is moved to closed position the switch actuating member 29 will ride up the sloping cam surface 58 to open the switch and extinguish the lamp.

While I have shown and described one embodiment of my invention, it is subject to many modifications. Changes, therefore, in the construction and arrangement may be made without departing from the spirit and scope of the invention as set forth in the appended claims.

What is claimed is:

1. An ash tray of the character described, including: a supporting frame; a receptacle mounted on said frame for movement between open and closed positions; a lamp housing on said frame exteriorly of said receptacle; a lamp mounted in said housing, said housing having a first opening for directing rays from said lamp toward said receptacle and a second opening positioned angularly to said first opening; a switch for controlling the operation of said lamp mounted on said frame adjacent said housing; and a baffle carried by said receptacle and extending adjacent said housing, said baffle having means for operating said switch to extinguish said lamp when the receptacle is closed, said lamp being adapted to be illuminated when the receptacle is partially open and fully open, and said baffle having a window adapted to be aligned with said second opening when the receptacle is in partially open position to admit a beam from the

lamp, said baffle blocking said beam when the receptacle is in fully open position.

2. Apparatus of the character claimed in claim 1, wherein said switch has an actuating member extending adjacent said baffle, and wherein the means for operating the switch comprises a raised surface on said baffle adapted to engage said actuating member when the receptacle is closed.

3. An ash tray of the character described, including: a supporting frame having a generally plane surface; an open-topped receptacle slidably mounted on said frame for horizontal movement between open and closed positions, said receptacle having a rear wall terminating below said surface to provide an opening into said receptacle; a lamp housing on said frame exteriorly of said receptacle; a lamp mounted in said housing, said housing having a first opening for directing rays from said lamp toward said receptacle and a second opening positioned angularly to said first opening; and a baffle mounted on said receptacle and extending adjacent said housing, said baffle having a window adapted to be aligned with said second opening when the receptacle is in one position to admit a beam from the second opening, said baffle blocking said beam when the receptacle is in another position.

4. An ash tray of the character described, including: a supporting frame having a generally plane top surface; an open-topped receptacle slidably mounted on said frame for horizontal movement between open and closed positions, said receptacle having a rear wall terminating below said top surface to provide an opening into said receptacle; a lamp housing on said frame exterior of said receptacle; a lamp mounted in said housing, said housing having a first opening for directing rays from said lamp toward said receptacle and a second opening positioned angularly to said first opening; a switch for controlling the operation of said lamp mounted on said frame adjacent said housing; and a baffle mounted on said receptacle and extending adjacent said housing, said baffle having means for operating said switch to extinguish said lamp when the receptacle is closed and said baffle having a window adapted to be aligned with said second opening when the receptacle is in partially open position to admit a beam from the lamp, said baffle blocking said beam when the receptacle is in fully open position.

5. An ash tray of the character described, including: a supporting frame; an open-topped receptacle mounted on said frame for movement into and out of said frame between a plurality of positions; a lamp fixedly mounted exteriorly of said receptacle, said lamp being located below the open top of said receptacle so that direct rays emitted thereby do not pass directly into said receptacle through the open top thereof in any position of the receptacle; means directing rays from said lamp into said receptacle; and a member carried by said receptacle having means for passing a beam of rays exteriorly of said receptacle from said lamp when the receptacle is in one position and means for intercepting the beam when the receptacle is in another position.

6. Apparatus of the character claimed in claim 5, wherein the member carried by the receptacle comprises a baffle mounted on the receptacle and extending away from said receptacle past said lamp, said baffle having a window so located that it passes a beam of rays from said lamp when the receptacle is in one position and said baffle having a body portion intercepting the beam when the receptacle is in another position.

7. An ash tray of the character described, including: a supporting frame; an open-topped receptacle mounted on said frame for movement into and out of said frame between closed, intermediate and open positions; a lamp mounted on the frame exteriorly of said receptacle, said lamp being located below the open top of said receptacle so that direct rays emitted thereby do not pass directly into said receptacle through the open top thereof in any position of the receptacle, said receptacle having a wall facing toward said lamp and being spaced from the supporting frame so as to define an opening through which rays pass from said lamp, means for directing said rays into said receptacle; and a baffle mounted on the receptacle and extending away from said receptacle past said lamp, said baffle having a window so located that it passes a beam of rays exteriorly of said receptacle from said lamp when the receptacle is in its intermediate

position, the body portion of the baffle intercepting the beam when the receptacle is in open position.

8. An ash tray of the character described, including: a supporting frame; an open-topped receptacle mounted on said frame for movement into and out of said frame between closed, intermediate and open positions; a lamp fixedly mounted exteriorly of said receptacle, said lamp being located below the open top of said receptacle so that direct rays emitted thereby do not pass directly into said receptacle through the open top thereof in any position of the receptacle, said receptacle having a wall facing toward said lamp and being spaced from said frame so as to define an opening through which rays pass from said lamp, means for directing said rays into said receptacle; a switch for controlling the operation of said lamp; and a baffle mounted on the receptacle and extending away from said receptacle past said lamp, said baffle having means for operating the switch to extinguish the lamp when the receptacle is closed and said baffle having a window so located that it passes a beam of rays exteriorly of said receptacle from said lamp when the receptacle is in its intermediate position, the body portion of the baffle intercepting the beam when the receptacle is in open position.

9. An ash tray of the character described, including: a supporting frame; an open-topped receptacle mounted on said frame for movement into and out of said frame; a lamp housing on said frame exteriorly of said receptacle; a lamp mounted in said housing, said lamp being located below the open top of said receptacle so that direct rays emitted thereby do not pass directly into said receptacle through the open top thereof in any position of the receptacle, and said housing having a first opening for permitting rays from said lamp to pass toward said receptacle, means for directing said rays in such a manner as to illuminate the receptacle and a second opening facing angularly to said first opening; a baffle mounted on the receptacle and extending away from said receptacle past said housing, said baffle having a window so located that it is aligned with said second opening when the receptacle is in one position to pass a beam of rays exteriorly of said receptacle from said lamp, the body

5

portion of the baffle intercepting the beam when the receptacle is in another position; a switch connected to said lamp; and means responsive to the movement of said baffle for closing the switch when the receptacle and baffle are in both said positions.

10. Apparatus of the character claimed in claim 9, wherein said directing means include a slot provided between the frame and a portion of the receptacle for admitting rays from said lamp which pass through said first opening in the housing, and means for directing said rays into the interior of said receptacle.

11. An ash tray of the character described, including: a supporting frame having a generally plane surface; an open-topped receptacle slidably mounted on said frame for movement into and out of said frame between closed, intermediate and open positions, said receptacle having a wall extending perpendicular to said surface and terminating short thereof to provide a slot which opens into said receptacle; a lamp mounted on the frame exteriorly of said receptacle, said lamp being located so that direct rays emitted thereby do not pass directly into said receptacle through the open top thereof in any position of the receptacle; a partition on said frame between the lamp and the receptacle, said partition having means for passing rays from said lamp toward said slot, means for directing said rays into the receptacle; and a baffle mounted on the receptacle and extending away from the receptacle past said lamp, said baffle having a window so located that it passes a beam of rays exteriorly of said receptacle from the lamp when the receptacle is in one position, the body portion of the baffle intercepting the beam when the receptacle is in another position.
